UNITED STATES PATENT OFFICE.

JOHN ASH SINGELLTON, OF COLUMBUS, OHIO, ASSIGNOR OF ONE-FOURTH TO LELAND S. DOUGAN, OF COLUMBUS, OHIO.

FROGLESS SWITCH.

Application filed February 17, 1928. Serial No. 255,100.

The invention generally relates to turnouts for guiding railroad and railway rolling stock during transfer of the same from one trackway onto or over another in its course over the roadbed and primarily has for its object to provide, for use in such turnouts, a frogless switch designed to eliminate the danger of derailment and the shocks and noise incident to the passing of 10 the wheels over the switch frog.

It is at present customary to provide in every turnout switch a frog or combination of rails arranged for the designed purpose of providing, as nearly as is possible, a surface 15 on which the broad tread of the wheel may always roll and a channel through which the wheel flange may pass, this equipment being at present necessary at each place where two rails intersect in acute 20 angular relation. Such frogs each include a "tongue" which terminates in an "actual point" and the sides or lateral edges of which connect with and form continuations of the intersecting rails, ("wing rails") one 25 of which parallels each lateral edge of the tongue in spaced relation to provide wheel flange passing grooveways and to constitute lateral guards and which are again bent outwardly each to align with the opposite 30 lateral edge of the tongue and to provide therebetween the frog "throat" through which the wheel flange passes in approaching or leaving the actual tongue point.

In the necessary provision in the switch frogs of the intersecting flange passing grooveways, an interval is made necessary during which the wheel is not supported in passing over the frog, and a wheel must 35 jump the gap between the "actual point" of the tongue to the wing rail portion defining the frog "throat". At this interval the wheel violently strikes the rail at the other side of the gap and distributes violent shocks and jars to the trackage and 40 rolling stock, and to assure any degree of safety during this moment of non-support guard rails must be provided, in addition to the wing rails, one inside and paralleling each outside rail of the merging tracks.

In its more detailed nature therefore, it is the purpose of my invention to provide as a substitute for the conventional frog a shiftable rail pivoted at the point of intersection of the rails and shiftable to align

the proper one of the intersecting rails with its extension, the said rail being properly associated with the switch proper to be shifted simultaneously therewith, thereby assuring smooth and safe passage of the 60 wheels over the intersecting rails without the necessity of wing rail or guard rail equipment.

With the above and other objects in view that will hereinafter appear, the invention 65 further resides in the novel details of construction, combination and arrangement of parts, all of which will be first fully described in the following detailed description, then be particularly pointed out in the 70 appended claim, reference being had to the accompanying drawing, in which:—

Figure 1 is a somewhat diagrammatic plan view illustrating the invention in use.

Figure 2 is an enlarged plan view of the 75 base plate and rail sections forming the frog supplanting portion of the invention.

Figure 3 is a longitudinal section taken on the line 3—3 of Figure 2.

Figure 4 is a cross section taken on the 80 line 4—4 of Figure 2.

Figure 5 is a diagrammatic plan view illustrating a conventional frog equipped "turnout".

Figure 6 is an enlarged diagrammatic plan view illustrating a conventional "frog".

In the drawing, in Figure 5, a conventional frog equipped turnout is shown and in this illustration the straightway track rails proper are indicated at 1 and the 90 merging or turn tracks proper are indicated at 2. The adjacent or inside rails intersect to form the "tongue" 3 of a "frog" and the said "tongue" terminates in the 95 "actual point" 4.

The customary "wing rails" are indicated at 5 and they are spaced from the tongue in parallel relation to its lateral edges to provide the wheel flange passing grooveways 6. After passing the "actual point" of the 100 frog the wing rails are again bent outwardly at 7 to align each with the lateral "tongue" edge opposite that with which it has previously been in parallel relation and to provide the frog "throat" 8.

By reference to the said Figure 5, and especially to Figure 6 in which an enlarged view of the conventional frog is disclosed, it will be observed that a gap 9 is provided over the "theoretical point" of the frog, in 110

which gap a wheel, in passing over from the "actual point" 4 to the "wing rail" extensions at the "throat," has no support and tends to drop down into the area approaching the throat.

This area of non-support causes the wheel to forcibly crash against the "actual point" or the wing rails at the "throat," depending on its direction of travel, with resultant excessive jar and shock distribution to the trackage and rolling stock, and much noise. Furthermore, because of the great dangers of derailment during this moment of non-support, outer guard rails 10 must be provided paralleling the outside rails 1 and 2 to guard against such derailment tendencies.

In the said conventional turnout the wing rail extensions continue to merge with the switch points 11 which are rigidly connected at 12 to be moved in unison by any suitable switch shifting mechanism generally indicated at 13.

In Figures 1 to 4 I have illustrated my invention, which is designed to overcome the structural objections enumerated above and to render unnecessary the employment of guard and wing rails, and consequently effects economies in rail construction in addition to the provision of safety factors.

In the frogless turnout shown in Figure 1 the straight trackways proper are indicated at 14 and the merging or turn rails proper at 15.

The rails of the trackways 14 and 15 which merge to intersect are suitably secured to the tongue or point 16 which is preferably cast integrally with the base member 17, which said base also has the spaced continuation rail sections or ends 18 cast thereon, (see Figures 1 and 2).

To the extensions 18 the switch point rails 19 are connected, and the said switch points are secured together to move in unison by the connector 20.

A shiftable rail section 21 is pivoted at 22 upon the base to form a continuation of the tongue 16 with its free end shiftable to align with one or the other of the extension rails 18 according to the position to which the switch points 19 are shifted. The free end of the rail section 21 is pin and arcuate

slot connected at 23 to the base and the swinging movement of the said rail is limited at its rail extension aligning position by 55 the upstanding stop lugs 24.

It will also be observed that the ends of the stop lugs 24 toward the tongue 16 are cut down as at 25 or cast lower than the wheel engaging face of the rail section 21 so that they will not interfere with free passage of the wheel flanges.

In order to provide for shifting of the swing rail section 16 in combination with the main switch points 19, the free end of the said rail is connected by the shifter bar 26 to a crank rocker rod 27 which effects the shifting of the main switch points 19 through the thrust connection 29. The rod 27 may be rocked to effect the desired simultaneous shifting of the switch points 19 and swing rail section 21 by any suitable mechanism generally designated 30.

In the foregoing description I have disclosed a particularly simple turnout 75 em- bracing a frogless switch in which smooth, safe, and practically noiseless travel of the wheels over the intersecting rails is provided for without the need of wing rails or guard rails.

From the foregoing description, taken in connection with the accompanying drawing, it is thought that the novel details of construction, the manner of use and the advantages of my invention will be readily apparent to those skilled in the art to which the invention relates.

What I claim is:

In railroad turnouts the combination with the intersecting rails and their extensions leading to switch points, of a pivoted rail section shiftable to align a selected intersecting rail with its extension, a longitudinal stop lug extending approximately the full length of the shiftable rail section and closely adjacent the said section at each side of its pivoted end and adapted to limit movement of the shiftable section at each rail extension aligning position, said lugs being reduced in height toward their ends 100 adjacent the pivoted end of the shiftable rail section to permit free passage of wheel flanges thereover.

JOHN ASH SINGELLTON.
